(57) **CLAIM**

The ornamental design for a front bezel for computer enclosure, as shown and described.

DESCRIPTION

FIG. 1 is a perspective view of a front bezel for computer enclosure showing our new design mounted on a computer enclosure;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof in using condition for explanatory purpose only and in a reduced scale, wherein the parts shown in broken line forms no part of the claimed design.

The broken line showing of a computer enclosure in the views is for illustrative environmental purposes only and forms no part of the claimed design.
